FIG. 2

FIG. 3

FIG. 4.

UNITED STATES PATENT OFFICE.

HORACE D. STEVENS, OF AKRON, OHIO, ASSIGNOR TO THE FIRESTONE TIRE AND RUBBER COMPANY, OF AKRON, OHIO, A CORPORATION OF OHIO.

ROTARY CUTTER.

Application filed July 24, 1925. Serial No. 45,806.

This invention relates to cutters and particularly to cutters for use in preparing short tube or rod sections from a long length of tubing or rod, one use of the device being to 5 cut radiator hose.

The general object of the invention is to provide a simple, inexpensive but highly effective device for rapidly cutting rod or tubing into sections.

10 Particular objects of the invention are to provide an improved rotary cutter head through which the material to be cut may pass, to provide a knife movable on the head inwardly to cut the material and to provide a simple means for operating the knife 15 on the rotary head.

Another object is to provide a gauge adjustable toward and from the cutter head to determine the length of tube or rod section 20 to be cut.

The foregoing and other objects are obtained by the construction illustrated in the accompanying drawings and described in detail below. It is to be understood that the 25 invention is not limited to the specific construction shown and described, nor is its use limited to the particular use set forth.

Of the accompanying drawings:

Figure 1 is a side elevation of a radiator 30 hose cutter embodying the invention;

Figure 2 is a section on line 2—2 of Figure 1;

Figure 3 is a section on line 3—3 of Figure 2; and

35 Figure 4 is a section on line 4—4 of Figure 2.

Referring to the drawings, 10 represents a base plate having mounted thereon a bracket 11 in which is mounted a hollow spindle 12, 40 providing a material feeding passageway and extending outwardly from bracket 11 as at 12^a and having journaled thereon a rotary head 13 formed with a sleeve 14 on which is secured a drive pulley 15 which may be 45 driven by a belt 16.

The head 13 carries a disk knife 17 mounted on a slide 18 movable radially on head 13 in a groove 19. To move the knife inwardly while the head 13 is rotated, sleeve 14 has 50 shiftably mounted thereon a hollow, frusto-conical, non-rotatable cam 20, the inner conical surface of which engages a frusto-conical roller 21 journaled on a spindle 22 secured on the outer end of slide 18.

55 For shifting cam 20 to operate knife 17,

a yoke 23, engaging pins 24, 24 on the cam member 20, is secured on a rock shaft 25 journaled on plate 10, shaft 25 having an operating lever 26 connected thereto.

There is arranged a gauge 27 comprising a flat plate secured onto a block 28 slidable in a bore 29 in a bracket 30. Block 28 has a screw 31 thereon onto which is threaded an adjusting wheel 32 and between plate 27 and bracket 30 about block 28 is a compression 60 spring 33. Bracket 30 is adapted to be secured in any of a plurality of positions relative to cutter head 13 by cap screws 34 engageable in any set of spaced threaded apertures 35, 35 in plate 10.

In use, bracket 30 is so positioned as to place plate 27 approximately the desired distance from cutter head 13. Adjusting wheel 32 is then actuated to accurately position the plate 27 to produce radiator hose of the desired length. Pulley 15 is rapidly driven by belt 16, thus urging knife 17 outwardly by centrifugal force so that roller 21 will ride on the inner surface of cam 20.

The vulcanized rubber tubing indicated at 80 T from which the hose sections are to be cut is fed through the hollow spindle 12 into engagement with plate 27. Lever 26 is now shifted to the right, thus shifting cam 20 to the right and causing roller 21 to move inwardly, thus actuating slide 18 inwardly forcing the rapidly revolving knife 17 through the tubing T. Roller 21 is all the while held in contact with cam 20 by centrifugal force. The cam 20 is then shifted to the left as viewed in Figure 1, thus permitting slide 18 to move outwardly to carry the knife 17 clear of the tubing, the cut section of which is withdrawn and the tubing again fed against plate 27.

90 It will appear from the foregoing that a device for rapidly and effectively cutting radiator hose sections and other tube or rod sections from a continuous length of material has been provided. It will also be apparent 100 that modifications of the invention may be resorted to without departing from the spirit thereof or the scope of the appended claims.

What is claimed is:

1. A device of the character described, comprising a rotatable cutter head, having a guiding passageway therethrough into which the material being cut slidably fits, a knife 105 slidable on said head across the passageway and normally urged outwardly on said head 110.

by centrifugal force, and means for urging said knife inwardly on the head while said head is rotating, said means comprising a roller connected to the knife, a shiftable hollow frusto-conical cam against the inner surface of which said roller engages whereby the cam limits outward movement of the knife and is adapted to be so shifted as to move said knife inwardly on the head to perform a cutting operation, and a gauge adjustable toward and from said head.

2. A device of the character described, comprising a rotatable cutter head, having a guiding passageway therethrough into which the material being cut slidingly fits, a knife slidable on said head across the passageway and normally urged outwardly on said head by centrifugal force, and means for urging said knife inwardly on the head while said

head is rotating, said means comprising a roller connected to the knife and a shiftable hollow frusto-conical cam against the inner surface of which said roller engages whereby the cam limits outward movement of the knife and is adapted to be so shifted as to move said knife inwardly on the head to perform a cutting operation. 20

3. A device of the character described, comprising a rotatable cutter head, having a passageway therethrough into which the material being cut slidingly fits, a knife slidable on said head across the passageway and normally urged outwardly on said head by centrifugal force, and means for urging said knife inwardly on the head while said head 25 30 35 is rotating.

HORACE D. STEVENS.
